UNITED STATES PATENT OFFICE.

WALTER A. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

COLLAPSIBLE LAST.

1,139,040.

Specification of Letters Patent.

Patented May 11, 1915.

Application filed June 12, 1914. Serial No. 844,665.

To all whom it may concern:

Be it known that I, WALTER A. KRENTLER, a citizen of the United States, and resident of Detroit, county of Wayne, State of Michigan, have invented an Improvement in Collapsible Lasts, of which the following description, in connection with the accompanying drawings, is a specification, like letters on the drawings representing like parts.

10 My present invention is an improved collapsible hinged last of the type illustrated in the prior Pym Patent No. 673,889, showing the original collapsible last construction. My present collapsible last is also intended

15 to employ the locking feature, and improved hinge construction, so far as the same is possible, of my prior patent 1,094,153. My said patent illustrates a novel form of knuckle joint last, with the hinge members

20 anchored at their ends most remote from the pintle or hinge pivot on which the parts swing, so that the solid wood of the last will take the strain and relieve the knuckle portion of the wood from the breaking

25 strain and pressures of lasting machines, leveling machines, heeling machines, and the like.

An important feature of my present collapsible last construction is that the hinge members constitute interlocking devices to aid in taking up the torsional twist and strain brought thereon, one hinge member being in the form of a rounded tubular member fitting snugly in a bored recess in one part, preferably the forepart of the last, and the other hinge member being a plate member, fitting tightly in a saw kerf of a width substantially equal to the width of the plate, and this plate is pivoted through the tubular member, which is slotted to receive the same. Furthermore, this plate is provided with an extension to engage the collapsible instep block and depress the same, automatically, when the forepart and heel part of the last

45 are broken or flexed for the removal from or insertion in a shoe. By having the plate member thus held by the walls of the saw kerf in which it fits and also fitting in the slot adapted to receive said plate at the

50 pivotal portion of the tubular hinge member, the tubular hinge is necessarily prevented from turning or twisting in the forepart, and therefore this tubular member does not depend wholly upon the rivet or pin which

anchors the remote end thereof for its torsional strength.

Other features of the invention, details of construction, and novel combinations of parts, will be hereinafter more fully pointed out and claimed.

Referring to the drawings, illustrating a preferred embodiment of the invention, Figure 1 is a side view of a last, with portions broken away, and a part of the locking device shown in cross section; Fig. 2 is a view of the last when flexed or collapsed, portions being broken away, and also parts being shown in cross section; and Fig. 3 is a top plan view of the hinge members.

I prefer to embody the present invention in the socalled knuckle joint or "Kant-brake" type of hinged last and to arrange the collapsible instep portion on a line of cut, and spring substantially as shown in United States Patent No. 947,972.

As illustrated in the annexed drawings, the forepart 1 of a divided last is provided with its instep portion 2 separated from the forepart 1 by a cut out section indicated by the curved lines of cut 4, 4 leaving the wood of the last of both sections 1 and 2 integral at the point 5. The heel part 3 is divided from the forepart 1 by a partially curved line of cut 6 and partially straight cut 7, to provide the knuckle joint construction explained in said prior Pym patent, the forepart and heel part being further provided with secant faces 8 and 9 respectively in the upper portion of the last to permit of the relative pivotal movement or flexing of the two parts when moved on the hinge members. In the forepart 1 I bore a recess 10 to receive the tubular hinge member 11, which member is anchored to the wood of the forepart by a pin 12 passing through holes provided therefor in the member 11, and through the solid wood portions of the last, remote from the pivot pin 13. The forward portion of the tubular member 11 is slotted at 14 to receive the hinge plate to be described, secured in the heel part. The heel part 3 has a vertical saw kerf 15 formed therein of appropriate width to receive the hinge plate 16, which plate is anchored to the heel portion by the pivot pin 17, passing through a hole therefor in the plate 16 and through the solid portions of the heel remote from the pivot pin 13, which pivot pin

also passes through a hole provided therefor in the forward portion of the plate 16, as clearly indicated in the drawings. This plate 16 is adapted to fit closely through the 5 slot 14 in the tubular member 11, so that it is firmly and pivotally pinned to said tubular member, as well as to the wood on either part of the member 11 in the projecting knuckle portion of the heel part. This knuckle portion is furthermore bored radially as indicated on the line 18, to receive the projecting end of the tubular hinge member 11, this boring being in effect a counter-boring partially included within the saw 10 kerf 15.

In order to effect the collapsing feature, depressing the instep block 2 when the last is collapsed and forcibly expanding the same when the last is straightened, the portion 2 15 is provided with a saw kerf 19 to receive the projecting portion 20 of the hinge plate 16, said projecting portion having a cam groove 21 formed therein and adapted to fit about a pin 22 passing through said cam groove 25 and through the wood of the last on either side of the saw kerf 19. The cam path 21 may end in a slightly enlarged seat 23 into which the pin 22 will "snap" when the last 30 is completely flexed and the instep portion 2 in final collapsed condition with the faces of the lines of cut 4, 4 in contact and the opposite secant faces 8 and 9 preferably also just in contact as illustrated in Fig. 2.

An automatic lock is provided, consisting 35 of an expansible coiled spring 24 and a plunger or ball 25, preferably of hardened steel, both being entirely concealed within the tubular member 11, with the spring 24 seated on the pin 12 and exerting expansive 40 tension through the ball 25 on the plate 16. To coöperate with the ball 25 and spring 24 I form the edge of the plate 16, where said plate is fitted through the slot 14 of the tubular hinge member 11, in the form of a 45 projection 26 and recess 27. The recess 27 is adapted to be engaged by the ball 25 when the last is in extended position and to thus constitute as firm a locking device as may be desired, requiring a strong initiative flexing, 50 breaking, movement, to start the flexing of the last, and force the ball 25 against the tension of the spring 24, until the projection 26 is moved to bring its main point below the diametrical line of tension on the ball 25. When the last parts are swung relatively by this line of tension, the continued 55 flexing movement will be easily effected, and the friction exerted by the ball 25 and edge of the plate 16 will hold the last in its flexed 60 position wherever moved. However, it is also desirable to provide a locking device for the last in extreme collapsed position, and to this end the recess 23 in the cam plate 21 is provided, into which recess the pin 22 will 65 snap as above explained.

The operation of the collapsible hinged last will, it is believed, be clearly understood.

The engagement of the cam plate 21 and pin 22 are such as to collapse or spring the instep portion 2 of the forepart 1 inwardly during the 70 flexing of the forepart and heel part on the pivotal hinge 13, while the reverse movement to expand the last, forces the instep portion 2 outwardly into its normal or expanded position by engagement of the pin 22 on the 75 shorter face of the cam groove 21. The arrangement of the tubular member 11 and plate 16 coöperate to greatly assist the entire last in maintaining its original form and rigidity, the plate 16 in the heel part, being 80 supported by the side walls of the saw kerf 15 as already explained. Furthermore the plate 16, having its forwardly projecting portion 20 firmly supported by the side walls of the saw kerf 19 in the instep portion 2 of 85 the forepart, aids greatly in holding the forepart, heel part and hinge member 11 all in proper alinement.

It will be appreciated that it is of great importance to maintain the forepart, heel 90 part and instep block in their normal relation, both in alinement and contact, especially in a collapsible last, to prevent any parts from working loose during use. As soon as a pivot, a last hinge, a bearing 95 socket, or the kerfs or sockets for the hinge parts, become the least worn, or loose, the forepart and heel part are quickly driven apart, lose their shape, style and usefulness, and the last is necessarily discarded. By 100 my present invention, utilizing the remote anchoring pins 12 and 17, and the coöperating supporting walls of the kerfs 15 and 19 for the hinge plate, to hold all the last parts, as well as the hinge member 11, in alinement 105 and position to resist torsional strain, I have produced a collapsible last capable of successfully withstanding the great strains incident to the use of modern high speed shoe machines, now in such general use. The 110 prior construction of collapsible lasts failed to stand up satisfactorily to these requirements, but my present invention has enabled collapsible lasts to be again commercially used under the present exacting shoe factory 115 conditions.

Having described my invention, what I claim as new and desire to secure by Letters Patent is:

A collapsible hinged last, having in combination, a divided forepart having a bored socket and a movable instep portion having a vertical saw kerf, a heel part having a vertical saw kerf in central, intersecting, longitudinal alinement with the rear of said 120 socket and with the first named saw kerf, a tubular hinged member, fitted in said bored socket in the forepart and projecting rearwardly from said forepart into the heel part where it is provided with a vertical slot 125 130

- alined with said two saw kerfs, and a hinged plate-member fitted in said saw kerf in the heel part in supported engagement with the walls adjacent said kerf, occupying the slot 5 in said tubular hinged member, and connected to the latter by a pivot pin in the heel part, passing through said rear outer end of the tubular hinged member, said plate-member having a projecting portion fitted 10 within the saw kerf of said instep portion and supported by the walls of said last mentioned saw kerf and having a cam groove
- and pin connection with said instep portion, and said tubular hinged member being transversely anchored at its forward end within 15 the forepart beyond its pivotal connection in the heel part, with said plate-member.
- In testimony whereof, I have signed my name to this specification, in the presence of two subscribing witnesses.

WALTER A. KRENTLER.
